TRAIN CONTROL SYSTEM

Alfred Ernest Hudd, Worth, Crawley, England

Application February 2, 1937, Serial No. 123,706
In Great Britain February 8, 1936

19 Claims. (Cl. 246—63)

This invention is for improvements in or relating to train control systems of the kind in which a receiver on the train is arranged to traverse and to be inductively influenced by, without contact with, two magnets disposed apart along the track at each signal location, whereby the receiver under the influence of the first magnet applies the brakes and/or operates a warning device and may be reset under the influence of the second magnet and in which means associated with the signalling system are provided for rendering the second of the magnets to be traversed operative or inoperative according to whether the signal is at "clear" or at "danger", respectively, and in which means under the control of the driver are provided for resetting the receiver.

According to this invention, a train control system of the kind referred to is characterized in that the receiver comprises a movable permanently polarized member with or without an associated collecting-plate and in that the two track magnets and permanently polarized member or collecting-plate are so relatively disposed and the polarized member is so initially set that an operative pole of each active track magnet influences the polarized member or said collecting-plate so as each to effect a single movement of the polarized member and in that the operative pole of each magnet and the permanently polarized member or collecting-plate overlap during traverse and one or both of them extend across the centre line of the track. Preferably, a single permanently polarized member is employed in the receiver which, together with the track magnets, are disposed along the centre line of the track. It will be appreciated that in referring to "two magnets" each magnet may be made up of a group of magnets but any one group of magnets effects but a single movement of the permanently polarized member. By "operative pole" is meant a pole which influences the receiver in such a way as to move the permanently polarized member. In an arrangement in which a collecting-plate is associated with the polarized member, only a single collecting-plate is arranged across the width of the track.

In one arrangement, according to this invention, the track magnets are so arranged with their poles along the length of the track that both poles are traversed in succession and so that the second pole is the operative pole and effects said single movement of the polarized member, while the first pole tends to keep said

member in the position to which it was last moved.

The single movement of the polarized member, when traversing a track magnet, may be effected by so arranging each track magnet that the lines of force from one pole only of each track magnet effectively influence the polarized member.

The polarized member may be arranged to be influenced only by the lines of force from one pole of each track magnet by so arranging the track magnet that only one pole is traversed. For example, by arranging the track magnet transversely to the direction of the track so that only one pole will be immediately beneath the receiver.

As already indicated, the train control system is of the kind including means under the control of the driver for resetting the receiver mechanism. These resetting means may cause the polarized member to be moved from the "brakes-on" position back again to its initial position. Preferably, the first magnet of each pair to be traversed is a permanent magnet and the second is an electro-magnet.

An important feature of the invention consists in that said polarized member comprises a permanent magnet. In an alternative construction, however, the polarized member may comprise an armature movably mounted in relation to and influenced by a fixed permanent magnet in the receiver.

A further feature of the invention consists in that the polarized member, whether it be a permanent magnet or an armature, is so mounted that between its limits of movement it is in unstable equilibrium, tending to remain at one of said limits. In this arrangement, when the polarized member comprises a pivoted permanent magnet, it may have associated therewith a fixed armature, so arranged that at each limit of movement of the permanent magnet, one or other of its poles is nearer the armature than the other, whereby there is a tendency for the permanent magnet to remain at either limit of its movement.

The effectiveness of the track magnets in moving the permanent magnet may be enhanced by the provision of a fixed collecting-plate on the receiver which is arranged to be influenced by the track magnets during the traverse thereof so that the collecting-plate temporarily becomes a magnet and which collecting-plate is so disposed in relation to the movable permanent magnet of the receiver that the latter is moved from one limit of movement to the other, when the

receiver traverses a track magnet. Preferably, the permanent magnet of the receiver is pivotally mounted and a collecting-plate is arranged so that a part thereof extends across the pivot axis on one side of the magnet. A second collecting-plate may be so disposed that a part thereof extends across the pivot axis on the opposite side of the permanent magnet, for example, one plate may be above and the other below the magnet, the upper one of which is preferably longer than the other. The purpose of arranging one collecting-plate to be longer than the other is so that when the shorter collecting-plate is over one pole of the track magnet, the longer collecting-plate may be influenced by the other pole and thus both poles of the track magnet may effect movement of the permanent magnet of the receiver.

It will be appreciated that it is necessary in a train control system of the kind referred to at the commencement of the specification for the movable member of the magnet of the receiver to be disposed comparatively close to the track magnet and thus there is the danger, unless precautions are taken to the contrary, for the receiver to be damaged by obstacles on the track. An important feature of the present invention consists in that the magnetic receiver is housed within a non-magnetic steel casing which, for example, may be formed from what is known as a non-austenitic stainless steel alloy.

In an arrangement in which the receiver comprises collecting-plates, one or both may form a closure for the casing. The casing may be dome-shaped and the upper collecting-plate may be arranged to form a closure member.

When a train control system according to the present invention is associated with a visual track signalling system, the track magnets may be located near any visual signal location in a number of different ways. For example, two track magnets may be located one after the other along the track near each visual signal location, either in close proximity to one another or disposed apart. Whichever arrangement is employed, the track magnet in each pair last to be traversed by the receiver is so controlled that it only energizes the receiver when the signal is clear. Where the magnets are in close proximity they will move the polarized member and return it again to its initial position in such rapid succession that the driver will not receive any indication in the cab. The object of disposing the two magnets of any pair apart is so that the driver may receive a short indication, for example on the warning device, when the signal is at "clear". In yet another arrangement of track magnets, two pairs of track magnets are disposed apart along the length of the track near any visual signal location, so that the last pair to be traversed is in close proximity to said location. The purpose of this arrangement is that after the first pair of magnets has given a warning to the driver that the signal is at "danger", he can slacken speed until such time as the second pair of magnets gives him a warning. On receipt of this second warning he should stop the train, and he will then be close enough to the visual signal to receive an indication from it when the track is again clear.

The above arrangements of track magnets are suitable for use with a signalling system in which a single visual signal concerning any particular line is provided at each location. For example, there may be disposed at successive locations on

the track a visual distant signal and a visual home signal. In such an arrangement, there may be arranged near each distant signal two track magnets disposed one after the other along the track and there are arranged near each home signal location two pairs of magnets, the magnets in each pair being arranged in close proximity, and the two pairs being separated along the length of the track, and, as already referred to above, the magnet of each pair last to be traversed by the receiver is provided with means which permit it to energize the receiver only when the signal is at "clear".

Where, at any signal location, there are two visual signals concerning any particular track, namely a visual home signal and a visual distant signal, two pairs of track magnets are disposed apart along the length of the track near the signal location and are so arranged that the pair last to be traversed by the receiver is in close proximity to the visual signals, the magnets in either pair may be either disposed apart or in close proximity but, preferably, the magnets in the first pair are disposed apart and the magnets in the second pair are in close proximity. Preferably, in any of the track magnet arrangements referred to above, each magnet is arranged with its poles apart along the length of the track.

In an arrangement in which the receiver controls the application of the brakes by opening a valve in the train-pipe, it is convenient for the valve to be located at a distance from the receiver, for example, in the driver's cab. Said valve may be operated by the receiver either through a pneumatic transmission or an electric transmission. Various methods of arranging transmissions are hereinafter described and claimed.

Such transmissions, in addition to controlling the application of the brakes, may also be arranged to operate an audible warning device. A feature of the invention consists in that a delay-action device is so associated with the train-pipe valve that the valve opens a predetermined time after the actuation of the warning device. This arrangement is particularly suitable for use with a track magnet system in which the magnets of a pair are disposed apart. In such an arrangement, when the signal is at "clear" both track magnets are energized. It is desirable that a warning shall be given without the application of the brakes. It will be appreciated that when the first magnet is traversed, the warning device will immediately come into operation, but owing to the delay-action device the brakes will not have been applied by the time the polarized member is returned to its initial position by the second track magnet.

It will be appreciated that where a pair of track magnets are provided, and also means for resetting the receiver member, the latter may be operated upon in any of three ways. When the track is clear, it will be given a double movement, i. e. two movements in opposite directions, by the two track magnets, and when the signals are at "danger" may either receive a single movement by one of the track magnets so as to apply the brakes, or it may be again returned to its initial position by the resetting means. It is convenient for the driver to know what operation took place at the signal location which was last passed and a feature of the present invention consists in the provision of a visual indicator which is so associated with the movable member of the receiver that three different indications are given according to

whether a single movement, a double movement or a resetting movement are given to the receiver member, any one of which indications, after being recorded, is retained until the indicator is next operated. Two different forms of indicator are hereinafter described and claimed.

The following is a description of certain alternative ways of carrying out the invention, reference being made to the accompanying drawings, 10 in which:—

Figure 1 is a diagrammatic sectional elevation of the apparatus on the train in which a pneumatic transmission is employed for transmitting the movement of the polarized member in the 15 receiver to the train-pipe valve,

Figure 2 is a diagrammatic plan view of the apparatus shown in Figure 1, and also showing the disposition of the track magnets for use with a signal system in which a single visual signal 20 concerning any particular line is provided at a number of locations on the track,

Figure 3 shows the disposition of the track magnets for use with a signal system in which at 25 each signal location on the track there is a visual distant signal and a visual home signal concerning any particular line,

Figure 4 is a somewhat similar diagrammatic view to Figure 1, showing an electrical transmission between the receiver and the train-pipe 30 valve,

Figure 5 shows an alternative arrangement for the electro-magnetic means which controls the train-pipe valve when a pressure system is employed instead of a vacuum system,

Figure 6 is a front elevation of one form of indicator,

Figure 7 is a section on the line 7—7 of Figure 6,

Figure 8 is a similar view to Figure 6 but with 40 the indicating dial removed,

Figure 9 is a fragmentary elevation showing the moving parts in a position when the track signals are at "clear",

Figure 10 is a section on the line 10—10 of 45 Figure 9,

Figure 11 is a fragmentary elevation showing the moving parts in a position when the track signals are at "danger" and a moment after the driver has operated the resetting mechanism,

Figure 12 is a section on the line 12—12 of 50 Figure 11,

Figure 13 is a fragmentary elevation showing the moving parts in the position they assume 55 after the driver has operated the resetting mechanism,

Figure 14 is a section on the line 14—14 of Figure 13, and

Figure 15 is a similar view to that shown in Figure 1 of an alternative form of receiver in 60 which a soft-iron pivoted armature is influenced by a fixed permanent magnet on the train.

Referring to the arrangements shown in Figures 1 and 2, the magnetic receiver comprises a permanent magnet 10 arranged with its poles disposed apart in the direction of the track. The permanent magnet is arranged to rock about a horizontal axis disposed transversely across the track and has secured to it an upwardly-extending arm 11 in which is loosely mounted a valve member 12. A fixed armature 13 having a collecting-plate 14 is disposed beneath the permanent magnet 10 and a similar armature 15 is disposed above the permanent magnet. The armatures are U-shaped so as to provide a pair of opposed projections at each end of the permanent 75

magnet. The opposed projections are disposed at such a distance apart and the pivot axis of the magnet 10 is so disposed in relation to the armatures that one end or other of the magnet tends to remain attracted towards one or other 5 of the projections. The armature 15, however, is provided with a longer collecting-plate 16 than the aforesaid collecting-plate 14. The length of the upper collecting-plate 16 is about the same as the length, namely 22 inches, of each track 10

magnet, one of which is indicated at 17 in Figure 1. The receiver also comprises a resetting mechanism for the permanent magnet 10. The resetting mechanism comprises a flexible dia- 15 phragm 18 which divides a casing 19 into two compartments 20 and 21, which diaphragm is urged by a spring 9 towards the right in Figure 1.

The compartment 21 is provided with a bleed-hole 22 communicating with the atmosphere. The compartment 20 communicates through a con- 20 duit 23 with a valve chamber 24. Normally, the conduit 23 is placed in communication with the atmosphere through an air filter 25 in the valve chamber 24 but when it is required to reset the permanent magnet 10, a slide valve 26 in the 25

valve chamber 24 is moved by a manipulating member 27 against the action of a spring 8 so as to connect the conduit 23 through another con- 30 duct 28 with a source of vacuum 29. Secured to the diaphragm 18 is a resetting rod 30 having a slot 31 formed therein through which the arm 11 extends. The resetting rod 30 also carries a re- 35 setting valve member 22. The resetting valve member and the valve member 12 co-operate with

two ports formed in a nose-piece 33 at the end of 35 a control conduit 34. It will be seen from Figure 1 that the permanent magnet 10, the armature 13 and its collecting-plate 14, the armature 15, the diaphragm casing 19 and its associated parts are 40 all housed within a casing 35 which is dome-shaped and has its closed end directed downwardly. The casing is closed at its top by the collecting-plate 16. The function of this casing is two-fold. It prevents the parts of the receiver 45 housed therein from mechanical damage through obstructions on the track and also shields them from dust and dirt. The casing requires to have considerable strength and is formed from a non-austentic stainless steel alloy in order not to interfere with the operation of the permanent track 50 magnets. The casing is circular and is of a suitable size to house the lower collecting-plate which is a disc 6 inches in diameter. The upper collect- 55 ing-plate is 22 inches by 10 inches wide and is secured by bolts 36 to flange 37 formed at the upper part of the casing 35. A sealing ring 38 is disposed between the upper collecting-plate and said flange. The interior of the casing 35 com- 60 municates with the atmosphere through an air filter and moisture-absorber indicated generally 65 at 39. The moisture-absorber may comprise silica gel.

The control conduit 34 communicates with what is termed hereinafter "a governor-type relay device." These words are intended to include any 65 arrangement in which under normal conditions, i. e. when the receiver is not influenced by a track magnet, pressure is balanced on either side of a diaphragm or plunger which is arranged to control the brakes and/or the warning device either 70 directly or through a second "governor relay device" and in which means controlled by the receiver are arranged to upset said balance of pressure, whereby the plunger or diaphragm is caused to move and thereby operate the brakes and/or 75

warning device. One specific form of governor-type relay device comprises a chamber 40 which is divided into two compartments 41 and 42 by a flexible diaphragm 43. The lower compartment 42 communicates with the control conduit 34 and the upper compartment communicates through a conduit 44 with the aforesaid source of vacuum 29. The diaphragm 43 has secured to it a valve spindle 45 and also has formed in it a bleed-hole 46 so that the pressures in the two compartments 41 and 42 may become equal. A compression spring 46 urges the flexible diaphragm towards the compartment 42. The valve spindle 45 extends through a valve chamber 48 in one wall of which are provided three ports 49, 50 and 51. The port 49 communicates with a conduit 52 leading to a pneumatic horn 53. The port 50 communicates with the aforesaid conduit 44 which in its turn communicates with the source of vacuum 29. The port 51 communicates through a conduit 54 with a second governor-type relay device hereinafter described.

The aforesaid ports 49, 50 and 51 are controlled by a valve chest 55 carried by the aforesaid valve spindle 45. The valve chamber 48 communicates with the atmosphere through an air filter 56 and a bleed-hole 7.

At the top of the valve chamber is located a visual indicator 57 which is operated in the manner hereinafter described by the movement of the valve spindle 45.

The second governor-type relay device comprises a casing 58 divided into two compartments 59 and 60 by a flexible diaphragm 61. The compartment 60 communicates with the conduit 54 and with a small vacuum reservoir 62 through a conduit 63. The capacity of the vacuum reservoir is about .3 cubic feet. Secured to the diaphragm is a valve stem 64 which extends out through the compartment 59 and is provided at its outer end with a valve member 65 which controls the passageway 66 from the train-pipe 67 and puts said passageway into and out of communication with the atmosphere. Normally when the brakes are off the train pipe 67 is under vacuum. The upper compartment 59 also communicates with said passageway 66 through a suitable port 68. The opening movement of the valve member 65 is in opposition to a compression spring 69 and the extent of opening movement is controlled by a setscrew 70. The valve member 65 co-operates with a suitable valve seat 71. When the valve member is opened, the inflowing air may be caused to operate a siren 72.

The source of vacuum 29 comprises a reservoir 73 having a capacity of about 2 cubic feet which communicates with the train-pipe through a non-return valve 74. The operation of the device is as follows.

Considering again the receiver end of the mechanism, assuming the receiver is not over a magnet on the track, it will be appreciated that the permanent magnet will tend to remain in either of two positions, one in which the left-hand end is attracted to the bottom armature and the right-hand end to the upper armature, or the other where the left-hand end is attracted to the upper armature and the right-hand end to the lower armature. The ends of the magnet are maintained out of actual contact with the armatures by non-magnetic stops (not shown). Normally, the permanent magnet is arranged to remain in the first of these positions 75 and in this position it will be appreciated that

the valve member 12 closes the port with which it is associated. Also, the spring 9 in the compartment 20 will tend to maintain the resetting rod 30 in a position to close the other port in the nose-piece 32. Assume now that the receiver approaches a track-magnet which, it will be noted, is disposed with its poles along the track but which is differently oriented to the receiver magnet. As the receiver approaches the track magnet, the right-hand end of the upper collecting-plate will first come under the influence of the south pole of the magnet, but the projections of the armatures do not become polarized until the two collecting-plates are influenced respectively by the two poles of the track magnet. This takes place when the lower collecting-plate is under the influence of the south pole of the track magnet and the upper collecting-plate is under the influence of the north pole of the track magnet, whereupon the projections of the upper armature 15 will be given a north polarity and the projections of the lower armature 13 will be given a south polarity, which conditions tend to maintain the receiver permanent magnet in its initial position. Eventually, the lower collecting-plate will be mainly influenced by the north pole of the track magnet and the upper collecting-plate by the south pole of the track magnet. Under these conditions, the projections of the upper armature will be given a south polarity and the projections of the lower armature a north polarity and the permanent magnet will thus be moved. In Figure 1 of the drawings, the permanent magnet is shown in an intermediate position during this movement.

As soon as the permanent magnet 10 moves, the valve member 12 will cause the conduit 34 to be placed in communication with the interior of the casing 35, and thence with the atmosphere. The balance of pressure on the two sides of the diaphragm 43 will thus be upset and the diaphragm will rise, carrying the valve chest 55 to its uppermost position. In this position, the pneumatic horn 53 will be placed in communication with the vacuum reservoir 73 via the ports 49 and 50 and conduit 44. Thus, the horn will sound. At the same time, the conduit 54 will be placed in communication with the atmosphere through the air filter 56. Thus, the balance of pressure on the two sides of the diaphragm 61 will be upset as soon as air has sufficiently filled the small vacuum reservoir 62. Thus, after a delay, the diaphragm 61 will rise and open the train-pipe 67 to atmosphere through the passage 66, between the valve member 65 and the valve seat 71, and through the siren 72.

As will be explained with reference to Figure 2, if a signal is at "danger" the permanent magnet of the receiver is not again influenced by any track magnet until it has been reset. Thus, when the signal is at "danger", the driver will hear the horn sound and unless he resets the receiver within a given time, the brakes will be applied. To reset the receiver, the driver pushes the manipulating member 27 against the action of the spring 8, thereby moving the slide valve 26 which places both the conduits 28 and 23 in communication with the vacuum reservoir 73. Thus, the chamber 20 will be subjected to vacuum and the diaphragm 18 will move to the left, carrying with it the resetting rod 30. The end of the slot 31 in the valve spindle will ultimately engage the arm 11 and bring the valve member 12 into contact with its associated port so as to close that port. In the meantime, the

valve member 32 will have uncovered its port. Thus, unless the manipulating member 27 is released, the brakes will be applied. Upon releasing the manipulating member 27, the vacuum in the chamber 20 will be destroyed and the resetting rod 30 will move to the right, causing the valve member 32 to close its port. The valve member 12 will maintain its port closed since, owing to the provision of the slot 31, the arm 11 5 will not again be engaged. The permanent magnet of the receiver in this manner is reset. As will also be explained with reference to Figure 2, when the track is clear and both a permanent magnet and an electro-magnet are active, 10 the receiver permanent magnet will open and close the valve 12 in such quick succession that the brakes are not applied.

It will be appreciated that in addition to the valve 65 for placing the train-pipe in communication with the atmosphere, there is also provided the usual brake control valve 7, as shown in Figure 2 of the drawings. Also shown in Figure 2 is a track magnet arrangement suitable for a signalling system in which there is only 15 one visual signal concerning any particular line at each signal location, that is to say, in which a distant signal is placed alone at one location and further along the track a home signal is placed alone. The visual distant signal is shown 20 at 76 (Figure 2) and the visual home signal is shown at 77. A permanent magnet 78 is placed in the middle of the track at a distance of about 630 feet from the visible distant signal location with its poles disposed apart along the 25 track so that the pole more remote from the signal is south. Thirty feet further on, and therefore 600 feet from the distant signal location, there is disposed an electro-magnet 79 with its north pole more remote from the signal. A 30 pair of contacts 80 are arranged in circuit with the electro-magnet and means are associated with the distant signal for closing the contacts when the signal is clear. In this latter case, both the permanent track magnet and the electro-magnet will affect the receiver. The permanent track magnet, as already explained, will cause 35 the horn to blow, but there will be a delay before the brakes are applied, and the energized electro-magnet will cause the permanent receiver magnet to be returned to its initial position before the brakes are applied.

Six hundred feet in front of the home signal 77 there are disposed a permanent track magnet 82 and an electro-magnet 83 arranged end-to-end in close proximity and with their south poles outermost. A similar pair of magnets comprising a permanent track magnet 84 and an electro-magnet 85 are disposed in like manner in close proximity to the home signal location. The electro-magnets 83 and 85 are arranged in 40 circuit with two pairs of electric contacts 86 and 87 and a source of electric supply 88. One pair of contacts, e. g., the contacts 87, are arranged to be controlled by the signal lever in the signalman's cabin, while the other pair of contacts 86 are arranged to be controlled by the movement 45 of the signal itself.

If the distant and home signals are at "clear" 50 the electro-magnets 79, 83 and 85 will be energized. Owing to the spacing apart of the track magnets 78 and 79, there will be sufficient pause 55 between the two movements of the receiver magnet as to permit a blast to take place on the horn but, as already indicated, there is not sufficient time for the brakes to be applied. On the other

hand, at the home signal, owing to the fact that in each pair of magnets the electro-magnet is disposed in close proximity to the permanent magnet, the two movements of the receiver permanent magnet will take place in such quick succession that no warning signal will be received. 5

If the distant and home signals are at "danger" 10 the electro-magnets 79, 83 and 85 are not energized. Under these conditions, the permanent track magnet 78 will move the receiver permanent magnet, the horn will blow and unless the driver resets the receiver, the brakes will be fully applied. He should know that he is at a distant signal and thus he will reset the receiver before the brakes are fully applied and should 15 proceed at a reduced speed. Finally, when the home signal is approached, he will get another blast on the horn, under the action of the permanent magnet 82 and he should know that he is about 20 600 feet away from the home signal. After resetting the receiver permanent magnet he should proceed with extreme caution until another blast of the horn takes place under the influence of the permanent track magnet 84; he should then bring the train to a standstill. He 25 should be able to see the visual signal even in foggy conditions and thus be able to ascertain when the track is again clear.

In Figure 3 is shown an arrangement of track magnets suitable for use with a signal system in 30 which, at each location on the track, both a visual distant signal and a visual home signal are provided. Near each such signal location there are disposed a permanent track magnet 90 and an electro-magnet 91 disposed about 30 feet 35 apart and arranged similarly to the pair of magnets near a single distant signal as described above. Each such pair of magnets is disposed about 600 feet away from the visual signal location which is indicated at 92. Situated in close 40 proximity to each visual signal location are a permanent track magnet 93 and an electro-magnet 94 placed end-to-end in close proximity to one another and arranged similarly to the pair of magnets in close proximity to a single home 45 signal as described above. The electro-magnets 91 and 94 are connected in parallel with a source of electric supply 95. Three pairs of contacts 96, 97 and 98 are provided in the circuit. The pairs of contacts 96 and 97 are arranged on 50 either side of the source of supply 95, one being controlled by the signal lever in the signalman's cabin and the other being controlled by the home visual signal. The pair of contacts 98 is arranged in circuit with the electro-magnet further from the visual signal location and is controlled by the movement of the visual distant signal. Thus, should the visual signals not respond to the signalman's control, the track magnets under such conditions must necessarily operate the warning device due to the fact that the electro-magnets are de-energized. Where both signals are at "clear", all the contacts are closed; 55 when the home signal is at "clear" and the distant signal is at "danger", the contacts 97 are 60 closed and the contacts 98 are open.

There are three possible signal conditions at each location and these will be met with in succession by the driver of a train travelling along a clear line towards a home signal at "danger". 70 He will receive the "all-clear" signal when the visual home and distant signals are both at "clear"; he will then come to a signal location at which the home signal is at "clear" and the distant signal is at "danger" while at the next lo- 75

cation he approaches, both signals will be at "danger". Where a system of light signalling is used, in the first case the green light will show, in the second case the amber light, and in the 5 third case the red light. These three conditions are now considered in turn.

If both signals are at "clear", both electro-magnets 91 and 94 are energized. Thus, the receiver permanent magnet will be returned to its 10 initial position each time it is moved by the track magnets 90 and 93. There will be time for the horn to be operated by the track magnet 90 since it is disposed away from the electro-magnet, but there will not be sufficient time for the brakes 15 to be applied. When, however, the receiver traverses the magnets 93 and 94, there will not be sufficient time even for the horn to be operated owing to the close proximity of the magnets to one another. Thus, in passing the signal 20 location, the driver will hear one blast on the horn but the brakes will not be applied.

If the home signal is at "clear" and the distant signal is at "danger", the electro-magnet 94 will be energized but the electro-magnet 91 will not 25 be energized. The permanent magnet 90 will move the receiver permanent magnet, the horn will blow and the driver should reset the receiver so as to prevent the brakes from becoming applied. When the train passes the visual signal 30 location, at which the second pair of magnets are located, no warning will be received on the horn owing to the close proximity of the permanent magnet and the electro-magnet.

If both signals are at "danger", neither of the 35 electro-magnets 91 and 94 will be energized; the permanent magnet 90 will move the receiver permanent magnet, the horn will blow, whereupon the driver should reset the receiver but reduce speed. After 600 feet the permanent magnet 93 40 will move the receiver permanent magnet, another blast on the horn will take place, and the brakes will be applied.

In any of the track signalling systems referred to above, instead of the magnets being arranged 45 with their poles disposed apart along the length of the track, they may be sunk in the track in an upright position and in such an arrangement the permanent track magnets will be arranged with their north poles uppermost and the electro-magnets with their south poles uppermost. 50 Alternatively, the magnets could be arranged so as to extend transversely in relation to the direction of the track, and so that only one pole is traversed by the receiver. In this case, the 55 north pole of the permanent magnet will be traversed and the south pole of the electro-magnet will be traversed.

It will be seen from the above description that in order that a driver shall know whether or not 60 to apply the brakes and reduce speed, he should know what was the nature of the last operation of the receiver, and to this end the aforementioned indicator 51 is provided. One form of indicator will now be described.

65 As already set out above, the indicator is operated by the valve spindle 45. The indicator may be used with either of the signalling systems. It will be remembered that at any signal location, when there is a signal at "danger", the 70 polarized member of the receiver is moved in one direction only by the track magnet and remains there until reset by the driver, and that at any signal location when the track is clear the polarized magnet of the receiver is first moved in one 75 direction by the permanent track magnet, and

then returned to its initial position by the electro-magnet. The indicator is arranged to show three conditions. First, when the track is clear, i. e. a condition which obtains when either the receiver permanent magnet has not been moved 5 at all or has been moved first in one direction and then quickly back again to its initial position by the track magnet. Second, when a signal has been at "danger" and the driver has reset the receiver permanent magnet, and, third, 10 a condition when a single signal is at "danger" and the driver has not reset the receiver permanent magnet. It will be noted from Figure 6 that these three conditions are marked on the indicator as "Clear", "Cancel" and "Caution". 15

As best seen from Figures 6 to 14, the receiver comprises an indicating hand 100 fixed to a hollow pivot pin 101 which is mounted on a peg 102 fixed to a back-plate 103. Mounted also on the hollow pivot pin is a sector-plate 104 having a 20 rim portion 105. Two pegs 106 and 110 are arranged towards the centre of the sector-plate and near the hollow pivot pin 101. An operating stem 107 is reciprocably mounted in the base 108 of the indicator, which operating stem is arranged to be engaged by the valve spindle 45. The operating stem is provided with a forked extremity 109 which is arranged to straddle the hollow pivot pin 101. A tension spring 111 is arranged to draw the sector-plate 104 towards the 30 right of Figure 7 and to maintain the peg 106 in engagement with the limb 112 of the forked member. Thus, upon raising the operating stem 107, the sector-plate will be rotated in an anti-clockwise direction until the peg 110 comes into 35 contact with the other limb 113 of the forked member. A detent member 114 is carried by a pivot pin 115 secured to the plate 103 and is provided with a notched extremity 116 comprising a cam-face 117 and a lip 118. Disposed beneath 40 the intermediate portion of the detent member 114 is a carrier member 119, which carrier member is reciprocable in a direction parallel with the axis of rotation of the indicating hand 100. The reciprocation of the carrier member is effected 45 by a flexible diaphragm 120 to which it is attached, which diaphragm is mounted in a compartment formed between the plate 103 and the back part of the indicator casing 121. The diaphragm is pressed towards the front part of 50 the indicator by a compression spring 122. The space to the rear of the flexible diaphragm communicates through a passageway 123 with a conduit 124 (see Figure 1) which latter conduit communicates with the conduit 23. Thus, when the 55 manipulating member 27 is operated to reset the receiver permanent magnet, the rear face of the diaphragm 120 is subjected to vacuum. The carrier member 118 is provided with a nose-piece 60 119 located beneath the intermediate part of the detent member 114, which nose-piece is provided with a cam-face 125 and a notch 126.

The operation of the indicator is now described. When the track signals are at "clear", 65 the operating stem 107 will be in its lowermost position and the peg 106 will rest on the limb 112 of the forked extremity 109. In this position, the sector-plate 104 will be directed upwardly with its rim portion 105 beneath the nose-piece 119 and out-of-contact with the detent member 114. The nose-piece will be in its forwardmost position with the detent resting at the top of the cam face 125 as indicated in the fragmentary view at the top of Figure 10. Under 70 75

these conditions, the indicating hand will point to the word "Clear".

Assuming now that the receiver passes a signal location at "danger", the receiver permanent magnet will be moved, causing the valve spindle 45 to be raised and the horn to blow, and these conditions will prevail until the driver resets the receiver permanent magnet. So long, however, as the horn is blowing and the brakes are applied, the valve spindle will remain in its uppermost position, whereby the sector-plate is moved to the left, as shown in Figure 11, and the indicator hand will point to "Caution". As soon as the driver operates the manipulating member 27 to reset the receiver permanent magnet, the rear side of the diaphragm 120 will be subjected to vacuum, the nose-piece 119 will be moved to the left, as in Figure 7, and the detent member 114 will drop into the notch 126, as shown in the fragmentary view shown in Figure 12. The valve spindle 45 will then descend, carrying with it the operating stem 107. The sector-plate 104 will be drawn to the right in Figure 13, and the rim portion 105 will enter the notched end 116 in the detent member 114. In entering the notched end, the rim will engage the cam-face 117 and lift the detent member 114 out of the notch 126, as shown in Figure 14. The rim 105 will be retained within the notched end by the lip 118 and thus the sector-plate will assume the position shown in Figure 13 and the indicator hand will point to "Cancel" from which the driver will know that he has acknowledged a warning signal. As soon as the receiver again traverses a permanent magnet on the track, the operating stem 107 will rise, causing the sector-plate to move to the left, and bringing the rim 105 out of the notched end. The spring 122, bearing on the diaphragm 120, will cause the nose-piece to move forward and the detent member to be raised to the position shown in Figure 10. Assuming the signal is at "Clear", the operating stem will descend to the position shown in Figure 9 and the sector-plate will return to the upright position shown in that figure.

The arrangement shown in Figure 4 is somewhat similar to that shown in Figure 1 with the exception that there is an electric transmission between the receiver and the parts of the mechanism in the driver's cab. The first governor-type relay device is replaced by an electromagnet 130 having a movable armature and actuating rod 131. The actuating rod is provided at one end with a valve member 132 and at the other end with a valve member 133. The valve member 132 controls a port 134 which on one side communicates through a bleed-hole 135 and an air filter 136 with the atmosphere and on the other side with a passage 137 which is connected to a conduit 138 which communicates with the relay device which operates the train-pipe valve in the manner described with reference to Figure 1. The other valve member 133 controls a port 139 which on one side communicates with the passage 137 and conduit 138 and on the other side with a conduit 140 which is connected direct to the train-pipe. The actuating rod and valve members are so arranged that when the electromagnet is energized, the port 134 is closed and the port 139 is opened, and when the electromagnet is de-energized, the port 134 is opened and the port 139 is closed. The electric transmission comprises a two-way switch having contacts 141 and 142, either of which may be engaged by a switch arm 143 moved by the receiver

permanent magnet. The switch arm 143 is connected by a lead 144 to one contact 145 of a two-way switch having a switch arm 146 connected to the positive side of an electric source of supply. The movement of the switch arm 146 is controlled by a manipulating member 147 which is employed for resetting the receiver permanent magnet. This is effected by moving the switch arm 146 into engagement with the other contact 148 of the two-way switch, which contact is connected by a lead 149 to a coil 150 which surrounds the lower armature 13. Another lead 151 from said coil 150 is connected to one end of a coil 163 situated at one side of an electro-magnetic relay switch 152, which coil 163 is connected at its other end to the negative side of the electric source of supply. A coil 164 situated at the other side of said electro-magnetic relay switch is connected at one end to the aforesaid contact 142 of the first said two-way switch through a lead 153, and at its other end to the negative side of the electric source of supply. An electric light coloured purple and indicated at 154 is connected to the contact 145 and through a lead 155. Another lead 156 from said purple light is connected to a contact 157 of the electro-magnetic relay switch. The switch-arm 158 of said latter switch is connected to the negative side of the electric supply. A second contact 159 of said switch is connected by a lead 160 to an electric light 161 coloured green. A second lead from said green light is connected to one end of the electro-magnet 130 and through a lead 162 to the contact 141 of the first said two-way switch. A yellow electric light 129 is on one side connected to the lead 153 and on the other side to the negative side of the source of supply. Said negative side is also connected to the electro-magnet 130. The switches are shown in a position when the track is clear. It will be seen that one side of the green light is connected to the negative source of supply through the lead 160, contact 159, and switch-arm 158, while the other side is connected through the lead 162, contact 141, switch-arm 143, lead 144, contact 145, switch-arm 146 with the positive side of the source of supply. In this position, the part 134 is closed.

Normally the green light will be lighted and when passing over a signal location at "Clear", the switch-arm 143 will be moved into contact with the contact 142 and then quickly back again to the contact 141. An electric bell is connected between the lead 153 and the negative side of the source of supply and as soon as the switch-arm contacts with the contact 142, the bell will sound, the green light will be extinguished, and the yellow light will light. When the switch-arm moves back into contact with the contact 141, the bell will stop ringing, the yellow light will go out and the green light will come on again. Should, however, the receiver pass a signal set at "danger", the switch-arm 143 will move into and remain in contact with contact 142, the green light will go off, the yellow light will remain lit and the bell will remain ringing until the manipulating member 147 is moved so as to bring the switch-arm 146 into contact with the contact 148. This will establish a circuit through the coil 150 and also through the coil 163 of the electro-magnetic relay device, which will cause the switch-arm 158 to contact with the contact 157, and also the coil 150 will reset the permanent magnet. When the manipulating member 147 is released, the switch-arm 146 will be moved

back into contact with the contact 145 and the purple light will light. Since the switch-arm 158 is no longer in contact with the contact 159, the green light will not be lit, so that the purple light alone will remain lighted. The last-mentioned conditions will prevail until the receiver again traverses a track magnet. The switch-arm 143 will then again be brought into contact with the contact 142, thereby lighting the yellow light and establishing a circuit through the coil 164 of the electro-magnetic relay switch, whereby the switch-arm 158 will again be brought into contact with the contact 159. If the track is clear, the switch-arm 158 will remain in this position and the green light will remain lit when the switch-arm 143 has returned into contact with the contact 141. If, however, the signal is at "danger", the driver will again operate the manipulating member 147 which will return the switch-arm 158 to the contact 157 and the purple light will again light up when the driver releases the manipulating member 147. It will be noted that so long as the driver holds the switch-arm 146 into contact with the contact 148, the electro-magnet 130 cannot be energized and that when the latter is in a de-energized condition, the brakes are applied. Furthermore, none of the lights will be lit.

In applying the electric control last described above to a brake system in which the brakes are applied by the release of pressure in a pipe-line, when the electromagnet 130 is not energized, the actuating rod 131 is in such a position that the valve 128 shown in Figure 5 places the train-pipe in communication with atmosphere through a whistle 165. As will be remembered, the electro-magnet 130 becomes de-energized when the receiver traverses a track magnet and the switch-arm 143 is brought into contact with the contact 142.

In Figure 5, the electro-magnet control valve is shown connected directly to the pipe-line instead of through a governor-type relay device, as described with reference to Figure 1 and to Figure 4.

In the construction shown in Figure 15, the receiver comprises a fixed permanent magnet 170 having two pole pieces 171, 172 which project downwardly towards the track and inwardly towards one another. An armature 173 in the form of a thin soft-iron metal plate is pivotally mounted between the two pole pieces, but has its axis 174 offset towards the track from the line joining the lower extremities of the two pole pieces. Thus, the armature tends to remain in either of its two limits of movement. The length of the armature is such as to leave a small gap between each end thereof and the adjacent pole. Two stops 175 and 176 are provided for engaging the two ends of the armature and preventing them from passing upwardly beyond the poles. The armature is arranged to control the main control valve 177 which opens up and closes communication between the train-pipe 67 and the atmosphere. The control valve may be connected to a diaphragm 179 which divides an airtight chamber 180 into two compartments 181, 182. Both of these compartments communicate through bleed-holes 183 and 184 with a vacuum supply and the compartment 182 communicates through a pipe-line 185 with a nose-piece 186A situated in the neighbourhood of the armature. This latter valve is so arranged that when the armature moves from a position in which the brakes are inoperative to a position where the brakes should

be operative, the valve opens the pipe-line 185 to the atmosphere through a port 187 in the valve casing and thus subjects the diaphragm 179 to a different pressure on either side thereof, causing it to move and open the main control valve, whereby the brakes are applied. In order to reset the pivoted armature to its initial position, there is provided in close proximity thereto a second airtight chamber 188 containing a diaphragm 189 dividing the chamber into two compartments 190 and 191. The compartment 191 communicates through a bleed-hole 192 with the atmosphere and the compartment 190 communicates through a pipe-line 193 to a resetting valve 194 disposed in the driver's compartment of the train and thence normally to atmosphere through the port 195. The resetting valve is so arranged that when operated it will close the port 195 and place the pipe-line 193 and the aforesaid compartment 190 into communication with a source of vacuum. Thus, the diaphragm 189 will be moved. The second diaphragm chamber 188 referred to above is disposed between the permanent magnet and the armature adjacent the pole-piece 171. Attached to the diaphragm 189 is a spindle 196, 25 arranged to project through a hole in the armature and provided with a knob 197 on the outer end thereof. It will be noted that the chamber is disposed above that end of the armature which is drawn downwardly when the brakes are applied 30 and thus the knob may be employed for drawing the armature up again when it requires to be reset. The valve 186 for operating the main control valve is also disposed between the magnet and the armature on the same side of the axis 35 of the armature as is the diaphragm chamber 188 but nearer to said axis. It comprises a valve-member 198 which is loosely mounted on the armature and which is arranged to co-operate with a port in the nose-piece 186A which nose-piece is disposed between the magnet and the armature. The magnet forms one wall of a casting (not shown) which hermetically encloses the armature, the valve and the diaphragm chamber. One of the walls of the chamber is provided with an air-filter and/or moisture-absorber 40 45 199.

I claim:—

1. A train control system comprising track magnets at various signal locations, a receiver on the train having a permanently polarized member mounted to move between fixed limits, a pneumatic brake system having a train-pipe valve, a governor-type relay-device controlling said train-pipe valve, a conduit extending from the receiver to said relay-device, a valve in said conduit operatively connected to said polarized member, means in the receiver which tend to retain the polarized member at either of said limits, each of which track magnets is so disposed in relation to the polarized member that when the magnets are traversed in the direction to which the signal applies, movement of the polarized member will take place only in one direction during said traverse to apply the brakes, 60 means associated with the signal system on the track for at times countering the effect of the track magnets on the receiver and means under the control of the driver for resetting the polarized member to a position to release the brakes. 65

2. A train control system comprising track magnets at various signal locations, a receiver on the train having a permanently polarized member mounted to move between fixed limits and located near the track, a pneumatic brake 75

system having a train-pipe valve operated by a governor-type relay-device, a second governor-type relay-device, a conduit operatively connecting together the two relay devices, a valve 5 operatively connected to the polarized member, a conduit connecting said valve to said second governor-type relay-device, means in the receiver which tend to retain the polarized member at either of said limits, each of which track 10 magnets is so disposed in relation to the polarized member that when the magnets are traversed in the direction to which the signal applies, movement of the member will take place only in one direction during said traverse to apply the brakes, 15 means associated with the signal system on the track for at times countering the effect of the track magnets on the receiver and means under the control of the driver for resetting the polarized member to a position to release the brakes.

20 3. A train control system comprising track magnets at various signal locations, a receiver on the train having a permanently polarized member mounted to move between fixed limits and located near the track, a pneumatic brake system having a train-pipe valve operated by a 25 governor-type relay-device, a second governor-type relay-device, a conduit operatively connecting together the two relay devices, a valve operatively connected to the polarized member, a conduit connecting said valve to said second governor-type relay-device, means in the receiver which tend to retain the polarized member at either of said limits, each of which track magnets is so disposed in relation to the polarized member that when the magnets are traversed in the direction to which the signal applies, movement of the member will take place only in one direction during said traverse to apply the brakes, 30 means associated with the signal system on the track for at times countering the effect of the track magnets on the receiver and means under the control of the driver for resetting the polarized member to a position to release the brakes.

35 4. A train control system comprising a number of visual signals, two track magnets located one after the other along the track near any visual signal location, means associated with the 40 visual signal for rendering the magnet in each pair last to be traversed to be operative when the signal is at "clear", a receiver on the train having a permanently polarized member mounted to move between fixed limits, a pneumatic 45 brake system having a train-pipe valve, a governor-type relay-device operatively connected to said train-pipe valve through a delay-action device, a valve operatively connected to said polarized member, a pneumatic horn controlled by 50 said governor-type relay-device, which track magnets and polarized member are so arranged that one track magnet effects movement of the polarized member in one direction and the other track magnet effects movement in the opposite direction, whereby the train-pipe valve opens a predetermined time after the actuation of said pneumatic horn.

55 5. A train control system comprising track magnets at various signal locations, a receiver on the train having a permanently polarized member mounted to move between fixed limits, a pneumatic brake system having a train-pipe valve, a governor-type relay-device controlling 55 said valve, a conduit extending from the receiver to said relay-device, a flat-faced valve member carried loosely by an arm attached to the polarized member, a valve seat having two ports therein, one of which is controlled by the aforesaid flat-faced valve member, a resetting diaphragm arranged to move both the polarized member and the flat-faced valve member, a second receiver 60 valve-member arranged to open the other port during the resetting of the polarized member and to close the port when the diaphragm returns to its initial position, a conduit extending from said ports to the relay-device, means in the receiver which tend to retain the polarized member at either of said limits, each of which track magnets is so disposed in relation to the polarized member that when the magnets are traversed in the direction to which the signal applies, movement of the member will take place only in one direction during said traverse to apply the brakes, 65 means associated with the signal system on the track for at times countering the effect of the track magnets on the receiver and means under the control of the driver for causing the resetting diaphragm to move the polarized member to a 70 position to release the brakes.

70 6. A train control system comprising two track magnets, one arranged after the other at each signal location, a receiver on the train having a permanently polarized member mounted to move 75

to said relay-device, a flat-faced valve member carried loosely by an arm attached to the polarized member, a valve seat having two ports therein, one of which is controlled by the valve member, a conduit extending from the other port of said valve seat to the relay-device, means in the receiver which tend to retain the polarized member at either of said limits, each of which track magnets is so disposed in relation to the polarized member that when the magnets are traversed in the direction to which the signal applies, movement of the member will take place only in one direction during said traverse to apply the brakes, 10 means associated with the signal system on the track for at times countering the effect of the track magnets on the receiver and means under the control of the driver for resetting the polarized member to a position to release the brakes.

15 6. A train control system comprising track magnets at various signal locations, a receiver on the train having a permanently polarized member mounted to move between fixed limits, a pneumatic brake system having a train-pipe valve, a pneumatic transmission between said polarized member and said valve, which polarized member is located near the track, means in the receiver which tend to retain the polarized member at either of said limits, each of which track magnets is so disposed in relation to the polarized member that when the magnets are traversed in the direction to which the signal applies, movement of the member will take place only in one direction during said traverse to apply the brakes, means associated with the signal system on the track for at times countering the effect of the track magnets on the receiver and a resetting member pneumatically connected with said polarized member and the valve controlled thereby.

7. A train control system comprising track magnets at various signal locations, a receiver on the train having a permanently polarized member mounted to move between fixed limits, a pneumatic brake system having a train-pipe valve, a governor-type relay-device controlling 45 said valve, a conduit extending from the receiver to said relay-device, a flat-faced valve member carried loosely by an arm attached to the polarized member, a valve seat having two ports therein, one of which is controlled by the aforesaid flat-faced valve member, a resetting diaphragm arranged to move both the polarized member and the flat-faced valve member, a second receiver 50 valve-member arranged to open the other port during the resetting of the polarized member and to close the port when the diaphragm returns to its initial position, a conduit extending from said ports to the relay-device, means in the receiver which tend to retain the polarized member at either of said limits, each of which track magnets is so disposed in relation to the polarized member that when the magnets are traversed in the direction to which the signal applies, movement of the member will take place only in one direction during said traverse to apply the brakes, 55 means associated with the signal system on the track for at times countering the effect of the track magnets on the receiver and means under the control of the driver for causing the resetting diaphragm to move the polarized member to a 60 position to release the brakes.

65 8. A train control system comprising two track magnets, one arranged after the other at each signal location, a receiver on the train having a permanently polarized member mounted to move 65

between fixed limits, a pneumatic brake system having a train-pipe valve, a governor-type relay-device controlling said valve, a conduit extending from the receiver to said relay-device, a valve 5 operatively connected to said polarized member, which pair of track magnets are so disposed in relation to the polarized member that one of them moves the polarized member in one direction and the other in the opposite direction, 10 means associated with the last track magnet to be traversed in each pair to render that magnet operative only when the track is clear, resetting means under direct control of the driver for resetting the polarized member from a "brakes-on" 15 position to a "brakes-off" position, an indicator operatively connected to the governor-type relay-device and with the resetting means so as to indicate either a single movement of the relay-device when one track magnet is operative, or 20 a double movement when both track magnets are operative, or to indicate the actuation of the resetting device.

9. A train control system comprising two track magnets arranged one after the other at each 25 signal location, a receiver on the train comprising a movable member adapted to control brake gear, which movable member and track magnets are so arranged that said movable member may be moved in one direction by one of said 30 track magnets and in the opposite direction by the other magnet, a resetting device for moving the movable member of the receiver from a "brakes-on" position to a "brakes-off" position, means for rendering the last magnet of each pair 35 to be traversed operative only when the track is clear, an electric indicator having three electric circuits each containing an electrically-operated visual indicator, a two-way switch controlling two of the circuits, which switch is operated by the movable member of the receiver, and the 40 third of which circuits is controlled by a switch operated by the resetting mechanism, whereby a different visual indication is given according to whether one track magnet is operative or two track magnets are operative, or according to 45 whether the resetting means have been operated.

10. A train control system comprising two track magnets arranged one after the other at each signal location, a receiver on the train comprising a movable member adapted to control 50 brake gear, which movable member and track magnets are so arranged that said movable member may be moved in one direction by one of said track magnets and in the opposite direction by the other magnet, a resetting device for moving the movable member of the receiver from a "brakes-on" position to a "brakes-off" position, means for rendering the last magnet of each pair 55 to be traversed operative only when the track is clear, an electric indicator having three electric circuits each containing an electrically-operated visual indicator, a two-way switch controlling two of the circuits, which switch is operated by the movable member of the receiver, and the 60 third of which circuits is controlled by a switch operated by the resetting mechanism, an electro-magnetic switch arranged in circuit both with the two-way switch and with the resetting switch in such manner that the operation of the 65 resetting switch to return the movable member to the "brakes-off" position causes the electro-magnetic switch to close the third circuit and to break the first two circuits and so that a subsequent movement of the movable member to a 70 position to apply the brakes opens the third circuit and closes the second, whereby a different 75

visual indication is given according to whether one track magnet is operative or two track magnets are operative, or according to whether the resetting means have been operated.

11. A train control system comprising two track magnets disposed apart along the track at each signal location, a magnetic receiver on the train, a movable permanently polarized member in the receiver adapted to control the brake gear and 10 so disposed as to come into the magnetic fields of the track magnets, means associated with the signalling system on the track for rendering the second track magnet operative only when the track is clear, which track magnets and polarized 15 member are arranged with their poles along the length of the track and so that the two poles of each track magnet are traversed successively by said polarized member and when so traversed in the direction to which the signal applies, the 20 approach of the leading pole of the first magnet tends to keep said polarized member at one limit of its movement, while the trailing pole effects movement of the polarized member to apply the brakes and the approach of the leading pole of 25 the second magnet tends to maintain the polarized member in the latter position, while the trailing pole returns the polarized member to its initial position to release the brakes when the 30 track is clear.

12. A train control system comprising two track magnets disposed apart along the track at each signal location, a magnetic receiver on the train, a permanent magnet mounted in said receiver to pivot about a horizontal axis 35 arranged transversely in relation to the track, which permanent magnet is adapted to control the brake gear, two fixed collecting-plates in said receiver, one arranged above and the other below the pivoted permanent magnet and both arranged 40 to extend along the length thereof from one pole to the other, the former of which collecting-plates is longer than the latter, and means associated with the signalling system on the track for rendering the second track magnet operative 45 only when the track is clear.

13. A train control system comprising two track magnets disposed apart along the track at each signal location, a magnetic receiver on the train, a permanent magnet mounted in the 50 receiver to pivot about a horizontal axis arranged transversely in relation to the track, two fixed collecting-plates in said receiver, one arranged above and the other below said receiver permanent magnet so as to extend along the 55 magnet from one pole to the other thereof and each provided with two projections so disposed apart as to lie opposite the poles of the permanent magnet, the upper of which collecting-plates is longer than the lower, and means associated 60 with the signalling system on the track for rendering the second track magnet operative only when the track is clear.

14. A train control system comprising two track magnets disposed apart along the track 65 at each signal location, a non-magnetic steel casing, open at the top and closed at the bottom, on the train, a single permanent magnet mounted in said casing to pivot about a horizontal axis arranged transversely in relation to the track, 70 two fixed collecting-plates, one arranged above and the other below said receiver magnet, the latter of which collecting-plates is disposed within the casing near the bottom thereof and the former of which collecting-plates is adapted to 75

close the opening at the top of the casing and to extend beyond either side thereof and means associated with the signalling system on the track for rendering the second track magnet operative 5 only when the track is clear.

15. A train control system comprising a visual distant signal and a visual home signal, two track magnets disposed one after the other along the track near each distant signal, two pairs of track magnets near each home signal, the magnets in each of the two latter pairs being arranged in close proximity and two pairs being separated along the length of the track, a magnetic receiver on the train, a movable permanent- 10 ly polarized member in the receiver adapted to control the brake gear and so disposed as to come into the magnetic fields of the two pairs of track magnets and to be moved in a single movement in one direction by an operative pole 15 of the first magnet of each pair to be traversed and in the opposite direction by an operative pole of the second magnet of each pair to be traversed, means associated with the signalling system on the track for rendering the second track magnet 20 25 of each pair operative only when the track is clear, which receiver and track magnets are arranged so that during traverse said operative pole of each track magnet overlaps a part of the receiver and so that at least one of the overlapping parts extends without interruption across the centre line of the track.

16. A train control system comprising both a visual home signal and a visual distant signal at any location on the track, two pairs of track magnets disposed apart along the length of the track near any such location so that the last pair to be traversed is in close proximity to the visual signal, which pair of magnets adjacent the visual signal location are in close proximity, whereas the other pair of magnets are disposed apart, a magnetic receiver on the train, a movable permanently polarized member in the receiver adapted to control the brake gear and so disposed as to come into the magnetic fields 30 35 40 45 of the two pairs of track magnets and to be moved in a single movement in one direction by an operative pole of the first magnet of each pair to be traversed and in the opposite direction by an operative pole of the second magnet of each pair to be traversed, means associated with the signalling system on the track for rendering the second track magnet of each pair operative only when the track is clear, which receiver and track magnets are arranged so that during traverse said operative pole of each track magnet overlaps a part of the receiver and so that at least one of the overlapping parts extends without interruption across the centre line of the track.

60 65 17. A train control system comprising two track magnets disposed apart along the track at each signal location, a magnetic receiver on the train, a permanent magnet pivotally mounted in the receiver adapted to control the brake gear, a fixed collecting-plate in the receiver arranged to extend along the pivoted permanent magnet from one pole to the other thereof, and

which is arranged to direct the magnetic field of the track magnets through said pivoted magnet so that it is moved in a single movement in one direction by an operative pole of the first magnet to be traversed and in the opposite direction by an operative pole of the other magnet, means associated with the signalling system on the track for rendering the second track magnet operative only when the track is clear, a pneumatic brake system having a train pipe 10 valve, an electric transmission between said pivoted permanent magnet and said valve, which transmission comprises an electro-magnet having a moving part connected to the valve, a second electro-magnet formed on said collecting- 15 plate and arranged to influence said pivoted permanent magnet, a reset switch in circuit with a source of electric power and said second electro-magnet, whereby the pivoted permanent magnet may be reset after being moved by a 20 track magnet.

18. A train control system comprising a number of visual signals, two track magnets located one after the other along the track near any visual signal location, a receiver on the train 25 having a movable member adapted to be influenced by the track magnets and adapted to control brake gear, one of which track magnets is arranged to move said receiver member in one direction while the other track magnet is 30 35 40 45 50 55 60 65 adapted to move the member in the opposite direction, means associated with the magnet last to be traversed by the receiver which render the magnet operative only when the signal is at "clear", whereby, when the signal is at "clear", the two track magnets at each signal location are adapted between them to give the movable member of the receiver a double movement and, when the track is at "danger", the movable member is given a single movement by the first track magnet, a resetting device under the control of the driver for giving a return movement to the movable member after said single movement, an indicator operatively connected to the movable member of the receiver and to the resetting mechanism, which indicator is adapted to indicate which of the aforesaid three movements was last effected.

19. A train control system comprising two track magnets at each signal location disposed apart along the track, each with its pole along the track, means associated with the signalling system on the track for rendering the second track magnet to be traversed operative only when the track is clear, a single pivoted permanent magnet on the train, two fixed collecting-plates arranged one above the other on opposite sides of the pivoted permanent magnet and each arranged to extend across both poles of the pivoted magnet, which collecting-plates and track magnets are disposed centrally along the track and the upper of which collecting-plates is longer than the lower in the direction of the length of the track for the purpose described.

ALFRED ERNEST HUDD.
